UNITED STATES PATENT OFFICE.

CLAUDE MORTIMER BROWN, OF BURLINGTON, VERMONT.

EVAPORATOR FOR MAPLE-SUGAR AND THE LIKE.

1,238,489.

Specification of Letters Patent. Patented Aug. 28, 1917.

Application filed July 1, 1915. Serial No. 37,484.

To all whom it may concern:

Be it known that I, CLAUDE MORTIMER BROWN, a citizen of the United States of America, and resident of 8 Latham Court, 5 in the city of Burlington, State of Vermont, in the United States of America, have invented certain new and useful Improvements in Evaporators for Maple-Sugar and the like; and I do hereby declare that the 10 following is a full, clear, and exact description of the same.

The invention relates to evaporators for maple syrup and the like, as described in the present specification and illustrated in the 15 accompanying drawings that form part of the same.

The invention consists essentially of the novel construction and arrangement of parts whereby the feed of the sap is automatically 20 controlled and directed throughout the containers so as to benefit by the distribution of the heating gases.

The objects of the invention are to increase the output in such devices, to economize 25 in the consumption of fuel, to insure the production of a syrup of superior quality and generally to provide an evaporator of simple design and of serviceable and durable construction.

30 In the drawings, Figure 1 is a side elevation of the evaporator.

Fig. 2 is a plan view of the evaporator.

Fig. 3 is a longitudinal section on the line 3-3 in Fig. 2.

35 Fig. 4 is a cross sectional view on the line 4-4 in Fig. 1.

Fig. 5 is a cross sectional view on the line 5-5 in Fig. 1.

40 Fig. 6 is an enlarged detail of the feed control.

Fig. 7 is an enlarged detail of the communications from the front to the rear sap pans.

45 Referring to the drawings, the furnace 1 having the fire box 2 and smoke pipe 3 supports the front and rear sap pans 4 and 5, said pans being separated by their end walls 40 and 50 respectively.

The pan 4 is divided into longitudinal 50 compartments by the partitions 41, through which are communicating ports adjacent to front and rear ends alternately, so as to insure the flow of the sap along each compartment in its circulation through the apparatus.

The pan 4 is set lower than the pan 5 in the furnace structure, thus while the hot gases from the firebox flow along the bottoms of both pans, they also pass through the tubes 42 which connect the combustion 60 chamber 43 with the smoke pipe 3, through each of the compartments formed by the introduction of the partitions 41 in the pan 4, said tubes being raised above the bottom of said pan and providing a considerable 65 addition to the heating surface.

The pan 5 is similarly divided into compartments by the longitudinal partitions 51, which have front and rear communicating ports alternately to secure the proper flow 70 of the sap over the heating surface.

The pan 5 has on one side adjacent to its rear end the opening 44 and on the opposite side similarly placed the opening 45.

The pan 5 through the sides adjacent to 75 its front end has the openings 52 and 53 respectively.

The boxes 54 and 55 are secured over the openings 52 and 53 and the pipes 56 and 57 lead from the openings 44 and 45 and form 80 the means of communication between said boxes and the pan 4.

The boxes 54 and 55 communicate as stated with the pan 5 and pipes 56 and 57 and also have each a discharge opening for 85 emptying the syrup during boiling operations. The valves 58 and 59 are opened respectively to effect the discharge from the one or the other side of the machine as the case may be.

90 The supplementary pan 6 is supported at the rear end of the pan 4 centrally and extends for a portion of the width of the larger pan, said supplementary pan being set on top of the partitions 41 and rigidly secured thereto and to the end wall 40.

The pan 6 is divided by the partition 13 into two compartments 60 and 61, said partition being slotted in its upper side as explained hereinafter.

100 The compartment 60 is the feed receiving chamber and the compartment 61 the feed delivery chamber and both form a primary heating pan.

The partition 13 is provided with ports 105 through which the sap flows from chamber 60 into chamber 61 and the side walls of the latter have the ports 62 through which the sap flows into the pan 4 and as these ports are toward the top of the walls the sap ob- 110

tains a preliminary heating and is therefore not delivered cold into the hot sap in said pan 4.

The supply pipe 7 is connected to a valve 8 shown in Fig. 6, the arm 9 of this valve being connected to the stem 10 of a float 11, as shown in Fig. 4.

The pan 6 as explained is divided by a partition 13 which supports the valve. This 10 partition has an opening hereinbefore mentioned at each end near the base to permit the liquid or sap to flow into the larger compartment thereof.

Plugs 14 are provided for the ports 62 15 of this pan 6 in the larger compartment thereof and also a plug 12 for one or other of the openings 44 or 45.

The operation is as follows:

Sap is supplied through the pipe 7, flows 20 into the smaller compartment of the pan 6 and through the openings in the partition 13 to the larger compartment of said pan. When sap rises to a certain height it flows 25 through the opening in the side of the pan 4 from which the plug 12 has previously been removed and thence into the pan 5 as indicated by the arrows. This sap winds its way through the partitions and in and over the air tubes and through the passage which 30 is shown in Fig. 7 to the rear pan 5 and in the course of the arrows to the passage on the opposite side from where it may be drawn off. When the sap has risen to a predetermined height, the float will automatically 35 shut off the valve 8 and stop the supply of sap. When the course of the sap is desired to be changed from one side of the pan to the other, the plugs 14 may be removed from the side of the pan on which 40 they are shown and put into the apertures on the opposite side. The float and valve may be turned around by means of the reduced portion in the partition 13 so that the float 11 will be suspended in the opposite 45 side of the pan 4. The plug 12 may be removed from where it is now shown and placed in a corresponding place in the opposite side of the pan. This will cause the syrup or sap to flow in a directly opposite 50 course to which it is now indicated.

A draw off pipe 15 is provided near the bottom of the pan and extends through the side of the combustion chamber 1 to facilitate the emptying of the evaporator.

Copies of this patent may be obtained for five cents each, by addressing the "Commissioner of Patents, Washington, D. C."

The valve 8 is supported by the bridge 80, 55 the latter having inwardly turned ends 81 engaging the flanges 82 and 83 of the wall of the pan 6 and partition 13 respectively, said partition flange 83 being cut out centrally to permit the removal and reversal 60 of the said bridge for transferring the valve 8 and its gear to the other side of the pan and thereby change the circulation of the sap and prevent the accumulation of a deposit in the pans common in such work. 65

It has been explained how as the sap enters from the feed pipe 7 it flows over the various heating surfaces of the pan 4 directed by the longitudinal divisions and through one or other of the pipes 56 or 57 70 in a box 54 or 55 and from there into the pan 5 flowing over the heating surfaces of said pan to the opening into the opposite box, where it is discharged through a valve pipe 58 or 59. The pipe 15 is connected with 75 the combustion gas passage for clearing out the gases preparatory to removing the boiling pans.

What I claim is:

In a maple sugar evaporator, a frame, front 80 and rear pans separated by a wall, a primary heating pan having a partition dividing it into two compartments for feed and delivery purposes to said front pan, said partition being formed to support a reversible 85 valve mechanism, said delivery compartment emptying into said front pan through overflow orifices at one side only, a feed pipe, a float control valve, an external passage at the opposite side from said overflow 90 orifices formed by a pipe from said front pan to an inlet chamber directly connected with said rear pan, a valve support on said partition and primary pan wall and removable therefrom and a valve and float gear 95 mechanism connected with said support and transferable from one side of the apparatus to the other and a similarly formed passage forming a discharge at the opposite side.

Signed at Burlington, Vermont, this fifth 100 day of May, 1915.

CLAUDE MORTIMER BROWN.
